UNITED STATES PATENT OFFICE.

JACOB S. JAMMER, OF NEW YORK, N. Y., ASSIGNOR TO WESTERN ELECTRIC COMPANY, INCORPORATED, OF NEW YORK, N. Y., A CORPORATION OF NEW YORK.

TRANSMISSION REGULATION.

Application filed November 26, 1924. Serial No. 752,319.

This invention relates to transmission regulation and is particularly adapted for use in repeatered transmission systems.

An object of the invention is to stabilize 5 the transmission characteristics in such systems.

A related object of the invention is to facilitate the maintenance of a transmission regulating system.

10 Another object of the invention is to provide a new and improved system for automatically adjusting the gain and level of each of a plurality of repeaters in a carrier current transmission system.

15 In long line transmission systems and repeatered radio systems, it is desirable to maintain the output of each repeater at the maximum operating level in order that the signal currents, which are greatly attenuated 20 during transmission, may be kept as far as possible above the noise level on the transmission line or other medium.

At the same time it is necessary to adjust 25 the repeater gains to compensate for changes in the transmission characteristics of the transmission line in order to maintain a constant overall equivalent. Otherwise, changes in the attenuation of a transmission line, due for example to varying weather 30 conditions, would result in large fluctuations in the volume of a telephone or other message being transmitted.

Various means have been proposed for 35 maintaining the output of such repeaters constant under varying conditions, such as measuring, indicating or controlling systems. It is well known, for example, that a pilot channel may be set aside in a multiplex signaling system, or a pilot circuit or 40 some other arrangement may be used in a transmission system, for the purpose of automatically adjusting the repeater gains to maintain them at the proper level.

In systems of this type, a pilot current is 45 usually impressed upon the transmission line at one terminal for transmission to another terminal geographically remote therefrom. At the intermediate repeater stations, the amplitude of the pilot current is used to 50 regulate the repeater gain. This is accomplished by connecting a detector to the output of each repeater, this detector being mechanically connected to a gain control potentiometer in the repeater circuit so that

a change in the repeater output produces a 55 compensating change in the repeater gain to restore the output level to normal.

Certain difficulties may arise, however, in gain control systems of the above type. For example, in a signaling system having four 60 repeaters, when the line section between a transmitting terminal and the repeater station nearest thereto increases in attenuation by say two miles, immediately the gain control mechanisms at every repeater on the 65 line respond to the decrease in level and each repeater is increased in gain by two miles. This results in a net decrease in overall transmission equivalent of six miles, that is, a two mile loss has been introduced upon 70 the line and an attempt has been made to compensate for this loss by introducing an eight mile repeater gain. Since there has been no change in the attenuation of any of the line sections except the first line section, 75 the repeaters associated with these other line sections would be operating at levels above the normal and accordingly they immediately begin to step the gain down, resulting in a swing in the opposite direction. This 80 hunting action will continue until each repeater in succession has reached the normal level.

In order to improve upon the operation of systems of this type, it has been proposed to 85 break up the gain control circuits into short lengths in such a way that each repeater is responsible for only the preceding adjacent line section. This is accomplished through the use of separate pilot oscillators 90 at each repeater for supplying pilot current to the next adjacent line section. In this way the gain control mechanisms at the various repeater stations will be unaffected by attenuation changes in a remote line section 95 which are intended to be compensated for at a preceding repeater station. Under certain circumstances, however, the attenuation of a given line section may vary to such an extent that the associated repeater 100 is unable to bring the output level back to normal thus resulting in fluctuations in the volume of the message being transmitted.

This invention provides a system of transmission control for automatically regulating 105 the transmission at each of a plurality of repeater points. Control mechanisms are provided at each repeater which are affected

only by line changes in the preceding line section unless such line changes are greater than a single repeater can accommodate, in which case the next repeater on the line is 5 called upon to make an adjustment in order to maintain a constant overall equivalent.

The invention will be described as applied to a multiplex carrier current telephone system, although it will be understood that it 10 may also be applied to other signaling systems.

The various features and advantages of the invention will appear from the following description and the accompanying drawings in which:

Fig. 1 is a schematic view illustrating the invention as applied to a plurality of repeater stations of a carrier current telephone system.

Fig. 2 is a diagrammatic view illustrating a terminal station of a carrier suppression telephone system embodying the invention.

Fig. 3 is a diagrammatic view of a carrier telephone repeater embodying the invention.

Reference will first be made to Fig. 1 which shows a carrier current telephone system having west and east terminal stations and a plurality of intermediate repeater stations R_1 , R_2 , R_3 and R_4 . In practice, it is 25 often customary to provide a repeater at the terminal stations as well as at the intermediate repeaters, the gain of the terminal repeaters being one-half as great as that of the intermediate repeaters.

The system of Fig. 1 diagrammatically illustrates the pilot control mechanisms for 35 adjusting the gains and levels of the repeaters employed for transmission from the west terminal to the east terminal. A similar 40 arrangement of control mechanisms is employed for adjusting corresponding mechanisms at the repeaters for transmission from the east terminal to the west terminal.

At the west terminal, in addition to the 45 usual signaling channel apparatus employed for the transmission of telephone messages, a pilot oscillator O_w is associated with the transmission line for the purpose of transmitting a pilot current of predetermined frequency to the repeater R_1 . A pilot detector D_1 is associated with the output circuit of the repeater R_1 and is adapted to control the gain potentiometer P_1 in the repeater 50 input circuit in accordance with the amplitude of the received pilot current, as will be hereinafter more fully described. The pilot current from oscillator O_w , however, is prevented from being transmitted to repeater R_2 by means of suitable wave filters, not shown. An independent pilot oscillator O_1 is provided at repeater R_1 for the 55 purpose of transmitting a pilot current to repeater R_2 .

The mechanisms at all of the repeater stations are identical, a pilot oscillator O_2 be-

ing provided at repeater R_2 for the purpose of transmitting a pilot current to repeater R_3 and a pilot oscillator O_3 being provided at repeater R_3 to transmit a pilot current to repeater R_4 , etc. At the east terminal, a 70 detector D_e in the output of the receiving amplifier or repeater serves to control the gain potentiometer P_e thereat.

The pilot detectors at the various repeater stations, in addition to controlling their respective gain potentiometers also serve to control the output of their respective pilot oscillators O_1 , O_2 , O_3 and O_4 in accordance with the amplitude of the received pilot current. In this way the control mechanisms at each repeater are affected only by line changes in the preceding adjacent line section unless such changes are greater than a single repeater can accommodate. In the event that this latter condition should prevail, the pilot oscillator at the repeater in the affected line section will automatically have its output adjusted by an amount dependent on the difference in the level obtained and the level required so that the 80 next repeater on the line is called upon to make an adjustment in response to the amplitude of the received pilot current in order to maintain a constant overall equivalent.

Normally, if a change in attenuation occurs in the line section between the west terminal and repeater R_1 , only repeater R_1 will make a gain adjustment. In the same way, if a change in attenuation occurs in the line section between repeaters R_1 and R_2 , only repeater R_2 will make the gain adjustment, etc. Under certain conditions, however, the attenuation of any line section, for example the line section between the west terminal and repeater R_1 , may increase 90 so much that the repeater R_1 is unable to bring the output level back to normal. In this case, the detector D_1 after increasing the gain of repeater R_1 to a maximum degree, then changes the output of pilot oscillator O_1 by an amount dependent on the difference in the output level obtained and the output level required. Thereupon, the control mechanisms at repeater R_2 in response to the change in amplitude in the received pilot current will increase the gain of repeater R_2 by the amount necessary to make up for the lack of gain in repeater R_1 . If repeater R_2 is unable to make up 100 the total gain required, the output of pilot oscillator O_2 is automatically adjusted to cause repeater R_3 to increase its gain, etc. In this way a portion of the loss originally introduced on the line section between the west terminal and repeater R_1 is shifted successively from one repeater to another until it is entirely compensated for by the total gain of the repeaters. If the attenuation of 110 any line section decreases, the gain potentiometers at the various repeaters will be 115 increased. The gain of the repeaters is 120 controlled by the pilot oscillators O_1 , O_2 , O_3 and O_4 respectively. The gain of the repeaters is 125 controlled by the pilot oscillators O_1 , O_2 , O_3 and O_4 respectively. The gain of the repeaters is 130 controlled by the pilot oscillators O_1 , O_2 , O_3 and O_4 respectively.

adjusted to introduce a compensating loss into the circuit to maintain a constant overall equivalent.

The invention is illustrated in detail in Figs. 2 and 3, which, when placed end to end with Fig. 2 at the left, represent the west terminal station and a mid-line repeater of a carrier telephone system interconnected by the multiplex transmission line ML.

The usual east terminal station, which is identical to the west terminal station shown in Fig. 2, is omitted for the sake of simplicity in the description. It will also be understood that although only one repeater station is illustrated in detail, a plurality of other repeater stations are also connected to the line in a manner similar to that illustrated in Fig. 1.

The terminal apparatus at the west station comprises a plurality of transmitting channels TC_1 and TC_2 connected through a common transmitting circuit TL to the main line ML , and a plurality of receiving channels RC_1 and RC_2 connected through a common receiving circuit RL to the main line ML .

Carrier currents are utilized for transmission over the line ML and are grouped as to their frequencies, the higher frequencies, as a group, being used for transmission from west to east, and the lower frequencies, as a group, being used for transmission from east to west.

A high pass grouping filter HP is paired with a low pass grouping filter LP at the west station. These filters serve to separate the directional groups of carrier waves to the respective terminal transmitting and receiving circuits. These filters and each of the other filters shown throughout the system may be designed in accordance with the principles set forth in the United States patent to Campbell, No. 1,227,113, issued May 22, 1917.

Low frequency lines L_1 and L_2 , which may be telephone lines or other types of signaling lines, are associated with channels TC_1-RC_1 and TC_2-RC_2 , respectively, for simultaneous and independent communication over the line ML with corresponding similar lines at the east station (not shown).

The low frequency lines are provided with balancing artificial lines or networks N_1 and N_2 , respectively, and with differential repeating coils H_1 and H_2 , commonly known as hybrid coils, for enabling independent transmission in the two directions between the line and the high frequency terminal apparatus.

Transmitting channel TC_1 includes a modulator M_1 and a band filter TBF_1 . Similarly, transmitting channel TC_2 , includes a modulator M_2 and a band filter TBF_2 .

Receiving channel RC_1 includes a band

filter RBF_1 and a demodulator and amplifier DA_1 , while channel RC_2 includes a band filter RBF_2 and a demodulator and amplifier DA_2 .

The modulators associated with the various transmitting channels throughout the system are of the balanced type disclosed in the United States patent to Carson, No. 1,343,306, issued June 15, 1920, designed to suppress the unmodulated carrier from transmission. The various demodulators and amplifiers may be of the well known vacuum tube detector type shown in Fig. 49 of an article entitled "Carrier current telephony and telegraphy" by Messrs. Colpitts and Blackwell, published in the Transactions of the American Institute of Electrical Engineers, Vol. 40, 1921.

The carrier system outlined above is, as stated, of the type in which the carrier wave of each channel is suppressed from transmission when no signals are being sent, and when signals are being transmitted modulation components of the modulated wave are sent over the line, but no unmodulated components of the carrier wave are transmitted. In order to reproduce the signal from modulated waves of this character, it is necessary that the carrier wave supplied to the demodulator at the receiver be of substantially the same frequency as the carrier wave which was suppressed at the transmitter. A system of this general character is described in connection with Fig. 49 of the Colpitts and Blackwell article, supra.

Carrier currents of the frequency assigned to channel TC_1 are supplied from a source TO_1 to the modulator M_1 wherein they are modulated by voice frequency currents or other signaling currents from the low frequency line L_1 . Carrier source TO_2 is similarly associated with modulator M_2 , while carrier current sources RO_1 and RO_2 are associated with the demodulators and amplifiers DA_1 and DA_2 , respectively.

As noted above, the carrier current sources RO_1 and RO_2 are necessary to supply to the incoming side bands in each receiving channel the carrier current which was suppressed at the transmitting end of the channel.

The various band filters associated with the terminal transmitting and receiving channels are so designed that they will transmit one of the side bands, either the upper or lower as desired, produced by modulation in the respective channels and will suppress from transmission frequencies lying outside of such band.

Voice frequency currents originating, for instance, in the low frequency line L_1 at the west station pass through the associated hybrid coil H_1 into the modulator M_1 in the transmitting channel TC_1 . There is likewise fed into the modulator the carrier current from the oscillator TO_1 , as described

above. Of the components of modulation appearing in the output circuit of the modulator M_1 , the transmitting band filter TBF_1 suppresses all except one side band, for example the upper side band, which it transmits or passes into the common transmitting circuit TL . The currents so transmitted from channel TC_1 and the other transmitting channels then pass through the high pass grouping filter HP to the multiplex line ML and thence through the repeater station to the east terminal where they are picked up by the high pass grouping filter thereat and are thence transmitted to the respective receiving channels.

Currents incoming at the west station pass through the low pass grouping filter LP , through a gain control potentiometer hereinafter to be described, to the common receiving circuit RL whence they are selected by the respective receiving band filters for transmission to the respective low frequency lines. Currents passing through receiving band filter RBF_1 , for example, are combined 25 in the demodulator and amplifier DA_1 with carrier waves from source RO_1 , and the voice frequency components of demodulation appearing in receiving channel RC_1 are transmitted through hybrid coil H_1 to the low frequency line L_1 .

In addition to the signaling channels indicated, a control or pilot channel is also associated with the line ML at the west station. The pilot transmitting channel comprises a pilot oscillator PO connected to the line ML through the pilot band filter PF_1 . The pilot oscillator PO is adapted to transmit a pilot current of a frequency different from that of any of the signaling channels, but within the upper group of frequencies transmitted by the high pass terminal filter HP .

The pilot receiving channel at the west station is connected to the line ML through the low pass grouping filter LP , variable potentiometer 5 and the pilot receiving band filter PF_2 , selective of the pilot frequency.

The pilot receiving channel may be of the type disclosed in U. S. Patent 1,579,708 to Jammer et al., April 6, 1926, and includes an automatic controlling device 6 for controlling the adjustment of the potentiometer 5 , a rectifier and amplifier 7 and an associated rectifier bridge RB .

The potentiometer 5 is arranged to be regulated automatically in accordance with the amplitude of the received pilot current to maintain the current impressed on the carrier receiving channels at a constant level. For this purpose the automatic controller 6 is arranged to move the variable taps of the potentiometer in response to slight variations in the received pilot current, the direction of adjustment of the potentiometer being always such as to compensate in the car-

rier receiving channels for variations in the received signaling currents.

The controller 6 may be of the type disclosed in the United States Patent to Brewer, No. 1,356,804, issued October 26, 1920, or any other suitable type of automatic controller.

The rectifier 7 is associated with the receiving pilot filter PF_2 through a transformer 8 . The rectifier bridge circuit, which is described in detail in the above mentioned patent of Jammer et al., comprises resistance elements 9 , 10 , 11 and 12 . The bridge is adjusted in accordance with the principles set forth in the Jammer et al. patent so that an unbalanced current flows in the resistance 11 , and is independent of the voltage fluctuations of the rectifier plate battery 13 within the desired operating limits. Due to this current, a steady drop of potential exists across resistance 11 except as it is altered by incoming variations from the line. The battery 13 is usually the plant battery at the local telephone exchange, or may be the plant battery for Morse telegraph lines. As it becomes discharged and as it is recharged its voltage changes. Due to the rectifier bridge circuit arrangement, however, these voltage variations have no effect upon the controlling and indicating circuit.

A galvanometer circuit is associated with the rectifier bridge and includes the galvanometer 14 , an adjustable portion of resistance 11 , an adjustable portion of resistance 15 , variable resistance 16 and a source 17 of constant potential. The galvanometer is adapted to control the operation of the automatic controller 6 .

The potentiometer control shaft 18 is operated by the motor 19 and is suitably geared to the variable taps on the potentiometer 5 so as to vary the voltage applied to the common receiving circuit RL .

Normally, resistance elements 11 , 15 and 16 are so adjusted that the currents in the differential windings of the galvanometer 14 are exactly equal under predetermined conditions of transmission on the line ML so that the galvanometer 14 is maintained in its zero or mid-position. As the attenuation of line ML departs from normal, however, corresponding variations occur in the strength of the received current. These current changes appear in amplified form in the resistance 11 , causing the galvanometer 14 to deflect and to effect such an adjustment of potentiometer 5 as will restore the current in branch 11 to its normal value. The adjustment of the taps associated with the resistance elements of potentiometer 5 introduces a compensating gain or loss, as the case may be, in the common receiving circuit RL , thus maintaining the received currents at a constant level.

The control apparatus 6 constructed in ac-

cordance with the Brewer patent, supra, not only serves to adjust the potentiometer 5 to compensate for variations in the received currents, but also is provided with a recording chart and associated mechanisms for making a permanent record of the variations produced by the deflection of the galvanometer 14.

Fig. 3 shows in detail the circuits employed at each of the repeater stations associated with the transmission line.

As pointed out above, the currents transmitted from the west station, which are impressed upon the repeater from line section W, are comprised in a higher frequency group than those transmitted from the east station which are impressed upon the repeater from line section E.

The repeater consists of upper and lower repeater branches which include one-way selective paths for each of the frequency groups. These selective paths include frequency discriminating filters which direct the incoming currents through the proper repeater channels.

The upper branch of the repeater includes a high pass input filter HPIF designed to pass frequencies of the upper group transmitted from west to east, an attenuation equalizer AE, gain control potentiometer 20, an amplifier WA and a high pass output filter HPOF. The transmission frequency range of the filter HPIF at each repeater station is sufficiently wide to include the frequency of the pilot generator while the range of the filter HPOF is not sufficient to pass the pilot frequency.

The lower branch of the repeater, as shown, contains a low pass input filter LPIF designed to pass frequencies of the lower group transmitted from east to west, an attenuation equalizer AE, an amplifier EA and a low pass output filter LPOF.

The attenuation equalizers AE may be of the type disclosed in the United States patent to Raibourn, No. 1,413,357, issued April 18, 1922, and serve to equalize the differences of line attenuation at the different carrier frequencies used, thus giving outputs from the repeaters of substantially equal value for the several frequency channels regardless of the line attenuation.

For the sake of clarity and simplicity in the description, the transmission regulating mechanisms of the invention are illustrated only in connection with the upper repeater branch for controlling the transmission of carrier currents transmitted from west to east. It will be understood, however, that similar regulating circuits are also to be employed in connection with the lower repeater branch at each repeater station for controlling the transmission of carrier currents from east to west.

At the repeater, carrier currents comprised in the upper group of frequencies incoming from line section W pass through the high pass input filter HPIF, attenuation equalizer AE, potentiometer 20, are amplified in amplifier WA and then passed through the high pass output filter HPOF to line section E. Carrier currents comprised in the lower group of frequencies incoming from line section E pass through the low pass input filter LPIF, attenuation equalizer AE, a potentiometer (not shown) similar to potentiometer 20, are amplified in amplifier EA and then transmitted through the low pass output filter LPOF to line section W.

The gain control mechanisms at the repeater station include the potentiometers 20 and 21 mounted on a common controlling shaft 22, a galvanometer 23 and an automatic controlling device 24 operated thereby.

The incoming pilot current in the upper branch of the repeater passes through the potentiometer 20 and amplifier WA and is selectively transmitted by a pilot filter PF₃ to the output of which is coupled the rectifier bridge circuit 25. The received pilot current, however, is prevented from being transmitted to line section E by the high pass output filter HPOF which suppresses currents of this pilot frequency.

A pilot oscillator PO₁ is provided at the repeater for the purpose of transmitting a pilot current to the succeeding line section E. This pilot oscillator is connected to line section E through the potentiometer 21 and pilot filter PF₄. A rectifier bridge circuit 100 26 is bridged across the output circuit of the pilot oscillator PO₁ between the potentiometer 21 and the pilot filter PF₄.

The rectifier bridge circuits 25 and 26 are similar to the rectifier bridge circuit described in connection with Fig. 2, the rectified current in the rectifier bridge circuit 25 setting up a direct current potential in an adjustable portion of resistance arm 27, and the rectified current in the rectifier bridge circuit 26 setting up a direct current potential in an adjustable portion of resistance arm 28. The potential set up in resistance 27 of rectifier bridge 25 is balanced against the potential set up in resistance 28 of rectifier bridge 26 in the differential galvanometer 23. The rectifier bridge circuits may be adjusted so that the potential set up in resistance 28 is exactly equal to the potential set up in resistance 27 when the amplifier WA is operating at its normal output level and the pilot oscillator PO₁ is passing the normal amount of pilot current to line section E. However, when the potential in resistance 27 departs from normal, due to changes in the amplitude of the received pilot current, the galvanometer balance will be upset and the galvanometer 23 will be deflected.

to effect such an adjustment of potentiometer 20 as will restore the current in resistance 27 to its normal value.

In describing the operation of the transmission regulating system at the repeater, let it be assumed that the line section W increases in attenuation so that the output level of amplifier WA is correspondingly decreased. Under such conditions the pilot current incoming from line section W is attenuated more than the normal amount and hence the direct current potential set up in resistance 27 is less than the direct current potential set up in resistance 28, since the pilot oscillator PO₁ is still operating at its normal output level. This condition upsets the voltage balance on the galvanometer 23 and causes the automatic controller 24 to set the adjusting mechanisms in motion, rotating the potentiometer shaft 22 in a counter-clockwise direction. As the shaft 22 rotates in a counter-clockwise direction the effective resistance introduced in the upper branch of the repeater by the potentiometer is increased, thus increasing the voltage drop in this circuit and correspondingly increasing the gain of the amplifier WA. When the output of the repeater amplifier WA is returned to a normal level the balance between resistances 27 and 28 is restored and the galvanometer 23 automatically stops the rotation of shaft 22.

Assuming, however, that the resistance elements of the potentiometer 20 moved along the adjusting taps until the maximum resistance is reached and still the output level of amplifier WA is below normal, it will be seen that it will then be impossible to set up a voltage balance between resistances 27 and 28 and hence the shaft 22 will continue to rotate in a counter-clockwise direction. As the shaft 22 continues to rotate the resistance elements of potentiometer 21 will move along the potentiometer taps and introduce a loss between the output of the pilot oscillator of PO₁ and the pilot filter PF₄. The voltage supplied to the rectifier bridge circuit 26, which is bridged across the output circuit of pilot oscillator PO₁ between potentiometer 21 and pilot filter PF₄ will be correspondingly decreased, and hence the direct current potential set up in resistance 28 of the rectifier bridge will be decreased until a voltage balance is established between resistance 28 of rectifier bridge circuit 26 and resistance 27 of rectifier bridge circuit 25. When such a voltage balance has been established the galvanometer 23 automatically stops the rotation of shaft 22.

It will be noted from the above description that the output of the pilot oscillator PO₁ has been decreased, and this decrease in output is exactly equal to the difference between the desired operating level and the level actually obtained in the output of the am-

plifier WA. Due to the decrease in the output of pilot oscillator PO₁ the next succeeding repeater on the line section E will immediately increase its gain to compensate for this apparent decrease in level. If the next repeater on the line is unable to make the necessary adjustments to compensate for this loss then the next repeater or repeaters on the line are called upon to make an adjustment, thus maintaining a constant overall transmission equivalent.

When the line section W decreases in attenuation the output of amplifier WA will increase correspondingly and the shaft 22 will be caused to rotate in a clockwise direction, and before it begins to decrease the gain of amplifier WA the output of the pilot oscillator PO₁ will be restored to normal.

It will thus be seen that the system functions to automatically maintain a constant overall equivalent at all times regardless of transmission changes on any line section.

The invention set forth herein is, of course, susceptible of various other modifications and adaptations and therefore is not to be considered as limited in any way except as defined by the scope of the appended claims.

What is claimed is:

1. A line divided into sections, repeater stations including repeaters connected between respective line sections, means at each repeater station actuated by current incoming over the adjacent line section to vary the gain characteristics of the repeater at that station to compensate for line transmission variations within predetermined limits, and means actuated in response to transmission variations in a line section exceeding said predetermined limits for varying the gain characteristics of a repeater at a repeater station on said line remote from said line section.

2. In a system of transmission regulation, a variable conducting path, a pair of terminal stations and an intermediate repeater associated with said path, means at one terminal for transmitting a control current over said path to said repeater, a separate source of control current at said repeater for transmitting a control current over said path to the other terminal, and means controlled by the control currents received at and transmitted from said repeater to indicate variations in the characteristics of said path.

3. In a system of transmission regulation, a variable conducting path, a pair of terminal stations and an intermediate repeater associated with said path, means at one terminal to transmit a control current over said path to said repeater, means at said repeater to transmit a control current over said path to the other terminal, a control device at said repeater, and means for im-

pressing potentials derived from the transmitted and received control currents at said repeater upon said device.

4. In a system of transmission regulation, 5 a variable conducting path, a pair of terminal stations and an intermediate repeater associated with said path, means at one terminal to transmit a pilot current over said path to said repeater, means including a 10 source of pilot current at said repeater to transmit a pilot current over said path to the other terminal, means for varying the pilot current transmitted from said source at said repeater under control of pilot current 15 received at said repeater from the terminal and means controlled by the transmitted and received pilot currents at said repeater to adjust the transmission of said conducting path.
- 20 5. In a system of transmission regulation, a conducting path whose transmission is variable under different conditions, a pair of terminal stations and an intermediate repeater associated with said conducting 25 path, means at one terminal to transmit a pilot current over said path to said repeater, means at said repeater to transmit a control current over said path to the other terminal, a current indicating device for said 30 repeater, means to differentially impress potentials derived from the transmitted and received pilot currents at said repeater upon said device, and means controlled by said device to adjust the transmission of said 35 conducting path.

6. In a system of transmission regulation, a variable conducting path, a pair of terminal stations and a repeater associated with said path, means to simultaneously transmit 40 a plurality of signals over said path by means of carrier currents of different frequencies, means to impress a pilot current upon said path at one terminal station, means to receive said pilot current at said 45 repeater, means to impress a second pilot current upon said path at said repeater, means to receive said second pilot current at the other terminal station, control apparatus at said repeater, means at said repeater to impress potentials derived from the transmitted and received pilot currents upon said control apparatus to adjust the 50 transmission of said conducting path, and means associated with said control apparatus and operable under predetermined conditions to adjust the pilot current impressed upon said path at the repeater.

7. In a signaling system in which a plurality of signals are simultaneously transmitted over a variable conducting path by means of carrier currents of different frequencies adapted to be amplified at a plurality of repeaters, the method of regulating the transmission of said signals which 60 comprises subjecting a pilot current to sub-

stantially the same conditions of attenuation as those affecting the signaling frequencies transmitted between successive repeaters, utilizing the pilot current received at one repeater to compensate for attenuation 70 changes in said conducting path, and utilizing the carrier current received at another repeater to compensate for such attenuation changes in said path as are not fully compensated for at said first mentioned repeater. 75

8. In a signaling system in which a plurality of signals are simultaneously transmitted over a variable conducting path by means of carrier currents of different frequencies adapted to be amplified at a plurality of repeaters, the method of regulating the transmission of said signals which comprises subjecting a pilot current to substantially the same conditions of attenuation as those affecting the signaling frequencies transmitted between successive repeaters, producing an indication at one repeater by means of the pilot current received thereat, adjusting the transmission characteristics of the conducting path in accordance with the indication produced, producing at another repeater by means of the pilot current received thereat an indication of the attenuation changes in said path which are not fully compensated for at said first repeater, and adjusting the transmission characteristics of the conducting path in accordance with the indication produced at said second mentioned repeater. 95

9. In a transmission system, a variable 100 transmission line, means for transmitting waves over said line, a repeater associated with said line, means responsive to changes in an incoming wave at said repeater to compensate for changes in the transmission characteristics of said line, a second repeater associated with said line, and means controlled from said first repeater to compensate at said second repeater for line changes which are not fully compensated for at said first repeater. 105

10. In a transmission system, a variable transmission line, means for simultaneously transmitting a plurality of signals over said line by means of carrier currents of different 115 frequencies, a repeater associated with said line, means to transmit a pilot current over said line to said repeater, means at said repeater responsive to said pilot current to compensate for changes in the transmission characteristics of said line, a second repeater associated with said line, means to transmit a pilot current from said first repeater to said second repeater, and means controlled by the pilot current received at said second repeater to compensate for line changes which are not fully compensated for at said first repeater. 120

11. In a transmission system, a variable 125 conducting path, a path of terminal stations

and an intermediate repeater associated with said path, means at one terminal for transmitting a control current over said path to said repeater, means at said repeater to transmit a control current over said path to the other terminal, means controlled by the transmitted and received control currents at said repeater to compensate for changes in the attenuation of said path, and means associated with said control means to adjust the pilot current impressed upon said path at said repeater in accordance with such attenuation changes as are not fully compensated for at said repeater.

15 12. In a transmission system comprising a line divided into successive sections, a pilot channel superposed on each successive sec-

tion, means at a terminus of each of a plurality of sections controlled by changes in the pilot current received over the corresponding section to indicate changes in the transmission characteristics of the line within predetermined maximum limits, and means associated with the first means and rendered responsive by changes in such pilot current in excess of those corresponding to said maximum limits for controlling the pilot current transmitted over the succeeding section of said line.

In witness whereof, I hereunto subscribe my name this 25th day of November, A. D. 1924.

JACOB S. JAMMER.
